UNITED STATES PATENT OFFICE.

JOHN W. ORAM, OF BALTIMORE, MARYLAND.

WHITEWASH-BRUSH.

SPECIFICATION forming part of Letters Patent No. 430,877, dated June 24, 1890.

Application filed March 7, 1890. Serial No. 342,965. (No model.)

To all whom it may concern:

Be it known that I, JOHN W. ORAM, a citizen of the United States, residing at Baltimore, in the State of Maryland, have invented certain new and useful Improvements in Whitewash-Brushes, of which the following is a specification.

This invention relates to an improvement in whitewash-brushes, and is illustrated in the accompanying drawings, in which—

Figure 1 is a side view of the bristle-block and the row of bottom bristle-knots. Fig. 2 is a side view of the head-block. Fig. 3 is a cross-section of the bristle-block with the band and all the bristles attached. Fig. 4 is a side view of the completed brush. Fig. 5 is a cross-section of the entire brush.

The brush has two separate blocks A B. The block A is a narrow one and has a longitudinal groove *c* on two opposite sides, a narrow bottom edge *d*, and a broader top edge *e*. The bottom edge *d* of the block A has holes bored to receive bunches or knots *f* of bristles, and crosswise of each groove *c* a row of side bristles *g* is placed and secured. The means for securing these side rows of bristles consist of an outside band *h*, extending entirely around the bristles and the block A, and a row of tacks *i* on each side driven 30 through the band and bristles into the block, said rows being parallel with the grooves *c*. The top ends of the side rows *g* are trimmed even with the surface of the top edge *e* of the narrow block A. Thus all three rows of the 35 bristles—to wit, the two side rows *g* and the bottom row *f* between the side rows—are secured to the narrow block A. If desired, cement may also be used, as usual, to assist in securing the bristles. The outside band *h* 40 should be metal, and preferably consists of tin-plate, and has a concavo-convex groove with the convex side facing the groove *c* in the block. This band *h* is broad enough to project upward above the top edge *e* of the 45 narrow block A, as at *h'* in Fig. 3, and thereby a socket *k* is formed over the entire top of the block A. By making the groove larger than the groove in the side of the block A and forming a bead *h*² even with the top 50 of the block the upper ends of the bristles are not compressed to such an extent as they are just below it, or within the groove in the

side of the block. In this manner the bristles are not so apt to come out, and the cement if applied to the top of the block will 55 pass down among the ends of the bristles and secure them more firmly than would be the case if the bristles were compressed so tightly that the cement could not penetrate among them. The head-block B is secured in the 60 socket *k*. This head-block has at its base two side flanges *l*, each being in the present instance beveled, and the base is thus broader than if there were no side flanges. The flanged base of the head-block B sets in the 65 socket *k* and comes in contact with the top surface *e* of the bristle-block. The upward projecting edge *h'* of the band surrounds the base-flanges *l*, and screws, nails, or tacks *m* driven through said band edge *h'* enters 70 sideways into the base of the head-block, and thus hold the head-block firmly.

This brush has great fullness for the quantity of bristles used, and is cheaply made and is durable.

Having described my invention, I claim—

1. A whitewash-brush having in combination an elongated bristle-block A, provided with a groove on two opposite sides, a row *g* of bristles on each side, secured crosswise of each groove, a row *f* of bristles on the bottom between said side rows, and a head-block B, secured to said bristle-block.

2. A whitewash-brush having in combination a bristle-block A, provided with a groove 85 on two opposite sides, a row *g* of bristles on each side, secured crosswise of each groove, a row *f* of bristles on the bottom between said side rows, a metal band surrounding the bristles on the bristle-block, and with one 90 edge projecting upward above said block and forming a socket, said band being provided with an outwardly-projecting bead *h*² at the top of the bristles *g*, a head-block having base-flanges which fit in said socket, and nails 95 through the band entering sideways into the said base.

In testimony whereof I affix my signature in the presence of two witnesses.

JOHN W. ORAM.
